FABRIC TREATING MACHINE

George H. Mason, Hawthorne, N. J.

Application June 16, 1934, Serial No. 730,872

7 Claims. (Cl. 26—11)

This invention consists in certain improvements in a mechanism of the class of that set forth in the Patent No. 1,757,536 to Arthur C. Mason, to wit, a mechanism by which loops left on a fabric in the weaving thereof are parted, to be afterwards removed by a shearing operation. The said improvements are directed to the means for mounting the float parting element and brush; the construction of said element; and the combination with said element of means which insures the parting of the floats before they can become appreciably wrapped around said element.

In the drawings:

Fig. 1 is a side elevation of the improved mechanism;

Fig. 2 is an elevation as viewed in the direction of the arrow *x* in Fig. 1;

Fig. 3 is a sectional view on the line 3—3, Fig. 2, with the parting element and brush in a plane perpendicular to the bar 9 and shows the parting element and its bearing in longitudinal section and the brush proper in outline.

Figs. 4 and 5 are fragmentary sectional views on the lines 4—4 and 5—5, respectively, Fig. 3;

Fig. 6 is an end elevation, partly in section, of the parting element and shows the brush in broken outline; and

Fig. 7 is a plan of a device which coacts with the parting element to insure parting of the floats.

On the frame 1 including uprights 2 are mounted the roller 3 and the bar 4 over which the fabric *a* spread transversely, extends, as it is drawn lengthwise, so that between the bar and roller it stands stretched in an inclined plane. The bar is rotatively adjustable in its bearings 5, as by having a flat 6 (Fig. 3) within one bearing 5 abutted by two set-screws 7 at opposite sides of a plane coincident with the bar's axis; by screwing either screw out and the other in the rotative adjustment of the bar is effected.

A sleeve-like carriage 8 is movable along the bar and has affixed thereto and projecting therefrom through one bearing 5 a rack 9 which is slidable in a groove 10 in the bar, whereby incidentally the carriage is in effect splined to the bar. The bar near said bearing has an arm 11 in which is journaled the shaft 12 of a pinion 13 engaged with the rack, said shaft having a hand-wheel 14.

Carriage 8 is formed with a tubular bearing 8a right-angularly related thereto in which is secured by set-screw 15 a shaft 16. On this shaft are supported, as will now appear, the means to support the rotary parting element and brush.

17 is a bracket comprising two sleeves 17a and 17b having their axes at right angles to each other, sleeve 17b being offset toward the observer in Fig. 3 relatively to sleeve 17a. Sleeve 17a receives shaft 16 and is secured thereto by the screw 18. A part of this bracket is a spindle 19 affixed in sleeve 17b and which affords a bearing for the brush 20 having a pulley 21.

22 is a bracket comprising two sleeves 22a and 22b also having their axes at right angles to each other, sleeve 22b being offset toward the observer (Fig. 3) relatively to sleeve 22a. Sleeve 22a receives shaft 16 and may be secured thereto by a screw 18a (Fig. 2) corresponding to screw 18. Sleeve 22b has ball-bearings 23 for the spindle 24a of the float-parting element 24 and its pulley 25, said spindle having a shoulder 26 and a collar 27 abutting the said bearings and thus confining said element against axial movement.

The pulleys 21 and 25 are in the same plane and are engaged by an endless belt 28 also engaged with any rotating driver 29, the belt being preferably trained around the pulleys so as to drive the brush and element 24 in opposite directions.

The brush and element 24 are generally cylindrical and in their operative relation their peripheries contact or not, as desired, with the opposite faces of the fabric; (usually their axes will be substantially if not quite parallel). To bring them into such relation the bar is rotatively adjusted by means of the set-screws 7 so that their line of incidence will coincide with the plane of the portion of the fabric stretched between bar 4 and roller 3; they are adjusted around the shaft 16 to bring each to the desired angular relation to the path of travel of the fabric or they may be adjusted around the shaft so as to bring them into proper coactive relation to each other and then the shaft rotatively adjusted to bring them to the desired angular relation to the path of travel of the fabric; and the carriage is slid along the bar so that they will be positioned to receive the fabric between them. In the new position the carriage may be steadied by a screw 30 tapped into the carriage and adapted to bind against the bar.

The element 24 comprises, with end disks 31, cutter disks or knives 32 having sharp peripheries and disks 33 and 34 all keyed to the spindle 24a and with which the cutter disks alternate, disks 33 and 34 being also alternated with respect to each other and disks 33 being of less and disks 34 of greater diameter than the cutter disks. The disks are all clamped between the pulley 25 and a nut 35 secured on the free end of the spindle.

The peripheral portions of the disks 34 appear T-shaped in cross-section (Fig. 3) and all have, projecting in a common rotative direction, the hooks 34a (Fig. 6).

5 Of course, as in the mentioned Mason patent the brush and parting element may have such longitudinal extent as to operate on both warp and weft floats and they will be arranged usually more or less oblique to the path of travel of the 10 fabric so as to insure catching floats of both classes; in the present example, where floats occurring at the edge of the fabric are to be parted, said element and brush are shown as having only limited length. Trouble is experienced in the 15 floats or loops caught by the hooks, and supposed thereupon to be parted by the cutter disks, starting to wrap and sometimes actually wrapping around the element 24 without becoming parted, which of course mars the goods, where- 20 fore the invention includes the following:

A collar 36 having two arms 37 has clamped to its arms two blades 38 arranged in a plane substantially tangential to the collar and adjustable toward and from each other to vary the gap between them by having the bolts 39 which clamp them to the arms penetrating slots 40 in the latter. The collar receives the sleeve 22b of bracket 22 for the parting element and is clamped thereto by the screw 41 so that the blades will lie close to that face of the fabric which is opposed by the parting element. The edge floats are sometimes many inches in length. Since the parting element rotates in such direction that each hook nearest the fabric projects in the direction (arrow y, Fig. 1) in which the fabric is drawn, as by the beam 42 on which it is wound, there is opportunity for any float happening not to be severed to slip off the hook. But in any event when this device is employed, affording as it does only a limited gap receiving the nip formed by the brush and parting element and through which any float caught by a hook will tend to be drawn by the hook, the severing or other parting is usually effected before the float can become appreciably if at all wrapped around the parting element.

While I prefer that said device should actually form a gap (or include two blades) it will be understood that one blade (as the right-hand blade in Fig. 6) forms a float-abutment at that side of the line of closest approximation of the hooks to the fabric toward which they project as, in the rotation of said element, they successively depart from the fabric, such loop-abutment of itself producing a pronounced bend in any float or loop starting to wrap around said element, and thus insuring the parting of such float.

This device also acts as a guard to prevent the fabric, if sufficiently slack, otherwise possibly to be caught by the hooks 34a and perhaps do irreparable damage to the cloth. In addition there is this advantage; to wit, that any arching of a loop toward the parting element which the brush tends to effect is of relatively short radius, so that loops that otherwise might pass unparted are with assurance caught by the hooks, to be thereupon parted.

The side flanges formed on the disks 34 as an incident of their T-shaped form are of importance thus: Without such a flange adjoining a cutter 32 it is found that though a loop may be severed, as in an arc z (Fig. 6), sometimes the loop breaks off rotatively back of this point and lodges between the cutter disk and the disk having the hooks, and when such broken-off portions sufficiently accumulate the cutter disk becomes of

course ineffective to act. If the flanges are present each act as a guard or fender with respect to the corresponding cutting edge, appreciably obstructing the entrance of the broken off portion between the cutter disk and adjoining disk 34 so that said portions fall away from the parting element. 5

Having thus fully described my invention what I claim is:

1. A mechanism of the class described comprising a frame, a coactive rotary brush and float-parting element arranged to peripherally engage the fabric being treated at the opposite faces thereof, and means to support said brush and element on the frame including brackets on which they are journaled and a supporting member for said brackets angularly related to the axes of said brush and element and around which one bracket is adjustable independently of the other. 10

2. A mechanism of the class described comprising a frame, a bar rotatively adjustable therein around its own axis, said frame having means to support the fabric in a plane substantially parallel with the bar, a coactive rotary brush and float-parting element to peripherally engage the fabric at the opposite faces thereof, means, mounted on the bar, having bearings for said brush and element, and means to adjust the bar rotatively in each direction comprising screws 15 tapped into the frame and engaging the bar and respectively arranged to adjust the bar around its axis in opposite directions. 20

3. A mechanism of the class described comprising a frame, a bar therein, said frame having means to support the fabric in a plane substantially parallel with the bar, a coactive rotary brush and float-parting element adapted to peripherally engage the fabric at opposite faces thereof, supporting means on which said brush and element are journaled including a carriage 25 slideable along and splined to the bar and means on the frame for shifting the carriage along the bar. 30

4. A mechanism of the class described comprising a frame, a bar therein, said frame having means to support the fabric in a plane substantially parallel with the bar, a coactive rotary brush and float-parting element adapted to peripherally engage the fabric at opposite faces thereof, supporting means on which said brush and element are journaled including a carriage 40 slideable along and splined to the bar and having a rack extending lengthwise of the bar, and means to shift the carriage along the bar including a rotary member journaled in the frame and having a pinion meshing with the rack. 45

5. A mechanism of the class described comprising a rotary float-parting element having peripheral hooks projecting in one direction around its axis, supporting structure in which said element is journaled having means to support the fabric with one face thereof presented to the periphery of said element, and a float-abutment carried by said structure and extending substantially parallel with the axis of said element and close to said face of the fabric and also close to that side of the line of nearest approximation of the hooks with the fabric toward which they project as, in the rotation of said element, they successively depart from the fabric. 60

6. A mechanism of the class described comprising a rotary float-parting element having peripheral hooks projecting in one direction around its axis, supporting structure in which said ele- 65

ment is journaled having means to support the fabric with one face thereof presented to the periphery of said element, and means, carried by said structure and arranged close to said face of the fabric, forming a gap of limited width extending lengthwise of the axis of said element and having its sides both sides of the line of nearest approximation of the hooks with the fabric.

7. A rotary float parting element comprising a substantially circular cutter disk having a pe-

ripheral cutting edge, and a disk coaxial with and arranged close to but spaced from the cutter disk and having peripheral hooks all projecting in one rotary direction and crossing the periphery of the cutter disk, the second named disk having a side flange on each hook adjoining the cutter disk and arranged in a diameter exceeding that of the cutter disk.
